(57) **CLAIM**

The ornamental design for a display rack, as shown and described.

DESCRIPTION

FIG. 1 is a front perspective view of a display rack showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view thereof with the base turned approximately forty-five degrees with respect to the upper portion;

FIG. 9 is a front perspective view of the display rack of FIG. 8 with a roof and base skirt in dashed lines; and,

FIG. 10 is a front perspective view of the display rack of FIG. 8 with a thatched roof in dashed lines in an exploded view above.

The dashed broken lines in FIG. 7 indicating casters are for illustrative purposes only and form no part of the claimed design.

The dashed broken lines in FIGS. 9 and 10 indicating a thatched roof are for illustrative purposes only and form no part of the claimed design.

The dashed broken lines in FIG. 9 indicating thatched base side walls are for illustrative purposes only and form no part of the claimed design.
